UNITED STATES PATENT OFFICE

2,375,361

COMBINED BAR SUPPORT AND SPACER

Bror Hillberg, Chicago, Ill., assignor to Superior Concrete Accessories, Chicago, Ill., a partnership

Application June 17, 1944, Serial No. 540,806

12 Claims. (Cl. 94—8)

The present invention relates generally to combined supports and spacers for bars. More particularly the invention relates to that type of combined support and spacer which is primarily designed for use in connection with the formation of a concrete structure, such as roadway, and comprises a horizontal rectilinear series of upstanding chairs which are spaced equidistantly apart, embody at their upper portions pocket forming means for receiving and supporting a series of parallel horizontally extending longitudinally disposed bars, such as dowel or reinforcing bars, and also embody at their upper portions and directly beneath said pocket forming means, means for supporting a horizontally extending transversely disposed rod for maintaining or holding the bars in horizontal alignment.

As evidenced by United States Letters Patent No. 2,291,157, granted to me on July 28, 1942, it has heretofore been proposed to utilize in connection with a combined support and spacer of the aforementioned type wire formed U-shaped chairs and to weld the bottom pieces of the chairs to a horizontally extending transversely disposed spacer rod in order to maintain the chairs in a truly rectilinear series and hence cause them to support the dowel or reinforcing bars in parallel relation. In practice it has been found that although a combined support and spacer of the character disclosed in the aforementioned patent fulfills its purpose or function as a medium for supporting and spacing dowel or reinforcing bars it is, however, subject to the objection that it is bulky and difficult to transport and handle because of the horizontally extending transversely disposed spacer rod to which the bottom pieces of the wire formed U-shaped chairs are welded.

One object of the invention is to provide a combined bar support and spacer which is an improvement upon, and eliminates the disadvantages or defections of, previously designed combined bar supports and spacers of the same general character by reason of the fact that the pocket forming means at the upper portions of the chairs for receiving and supporting the dowel or reinforcing bars are so designed and constructed that they hold the bars truly normal or at right angles to the subjacent bar aligning rod and hence eliminate the necessity of employing or utilizing a horizontally extending transversely disposed spacer rod for maintaining the chairs in a truly rectilinear series.

Another object of the invention is to provide

10 a combined bar support and spacer of the last mentioned character in which the pocket forming means for receiving and supporting the dowel or reenforcing are in the form of elongated plate metal stampings and embody centrally disposed transversely extending semi-cylindrical pockets for the bar aligning rod and in addition longitudinally extending semi-cylindrical pockets which extend truly at right angles to the bar aligning rod and serve to receive and support the dowel or reenforcing bars.

15 A further object of the invention is to provide a combined bar support and spacer of the last mentioned character in which the side pieces that are at one side of the upstanding wire formed U-shaped chairs have the upper ends thereof fixedly connected to the plate metal stampings and the other side pieces at the other side of the chairs have the upper ends thereof 20 so arranged and formed that they serve to retain the dowel or reenforcing bars in their respective pockets in the stampings with a spring action.

25 A still further object of the invention is to provide a combined bar support and spacer which is generally of new and improved construction, may be manufactured at a low and reasonable cost and is characterized by simplicity of design and quick mounting of the bar aligning rod and the dowel or reenforcing bars.

30 Other objects of the invention and the various advantages and characteristics of the present combined support and spacer bar will be apparent from a consideration of the following detailed description.

35 The invention consists in the several novel features which are hereinafter set forth and are more particularly defined by claims at the conclusion hereof.

40 In the drawings which accompany and form a part of this specification or disclosure and in which like letters and numerals of reference denote corresponding parts throughout the several views:

45 Figure 1 is a perspective view showing a combined bar support and spacer embodying the invention in connection with a like combined support and spacer and forming therewith a unit for supporting a concrete roadway joint of the compressible filler strip and dowel bar type;

50 Figure 2 is an enlarged perspective view of the upper portion of one of the chairs of the combined support and spacer;

Figure 3 is an enlarged plan view of the chair shown in Figure 2; and

Figures 4, 5 and 6 are sections taken respectively on the lines 4-4, 5-5 and 6-6 of Figure 3.

The combined support and spacer which is shown in the foreground of Figure 1 of the drawings constitutes the preferred form or embodiment of the invention. It is designated or identified by the reference numeral 7 and is adapted in conjunction with a like combined bar support and spacer 8 to be used in connection with a concrete roadway joint J consisting of a compressible filler strip j and a series of parallel horizontally extending dowel bars j¹. The joint is adapted for disposition between a pair of adjoining roadway forming slabs S and S¹ on a sub-grade S² and, as well understood in the art, permits the slabs to expand and contract in response to changes or variations in the temperature of the surrounding atmosphere. The strip j is formed of composition material and fits in an upstanding position between the two concrete slabs. The dowel bars j¹ extend through circular holes in the central portion of the filler strip j and constitute load transfer members whereby the load on one of the slabs is transferred to the other slab. They are spaced equidistantly apart and extend lengthwise of the slabs and sub-grade. In addition they are located in a horizontal plane and are covered with grease or graphite so that during pouring of the concrete for the slabs the concrete will not adhere thereto. The joint also comprises in addition to the filler strip and dowel bars, a set of sheet metal sleeves j². These sleeves are slidably mounted on the ends of the dowel bars that are at one side of the strip j and form air pockets outwardly of such ends whereby sliding movement of the dowel bars is permitted in response to expansion of the slabs. As the result of the grease or graphite which is applied to the bars the bars, after setting of the slabs, are free to slide longitudinally and permit the slabs to move to and from one another in response to expansion and contraction thereof.

The combined bar supports and spacers 7 and 8 constitute a unit for holding the joint J in place during pouring of the concrete in connection with formation of the slabs S and S¹. They are adapted to become permanently bonded to the concrete and serve to reinforce the slabs S and S¹, respectively. The combined support and spacer 7 is located at one side of the compressible filler strip j of the joint and serves to support the adjacent ends of the dowel bars j¹. The other combined support and spacer, i. e., the combined support and spacer 8 is located on the other side of the strip j and is associated with, and serves to support, the other ends of the dowel bars.

The combined bar support and spacer 7 is disposed in substantially parallel relation with the compressible filler strip j of the roadway joint j and comprises a horizontal rectilinear series of separately formed and independent upstanding equidistantly spaced chairs 9 and a horizontally extending rod 10. The chairs correspond in number to, and are associated respectively with, the dowel bars j¹ and embody brackets 11 at their upper ends. The rod 10 extends transversely of the slab S and is disposed in parallel relation with the compressible filler strip j. It is carried by the brackets 11 as hereinafter described more in detail and serves horizontally to align the adjacent ends of the dowel bars j¹. As shown in Figure 1 the rod 10 is supported by the chairs 9 in elevated relation with the subgrade S² and

when in place underlies and directly engages the adjacent ends of the dowel bars.

The chairs 9 are U-shaped in design or contour and are formed of comparatively stiff wire. They are adapted to rest upon, and extend upwards from, the subgrade S² and consist of straight horizontally extending bottom pieces 12 and upstanding side pieces 13 and 14. The bottom pieces 12 extend obliquely or angularly to the horizontally extending transversely disposed bar aligning rod 10, as shown in Figure 3. They are adapted to rest flatly upon, and engage directly, the subgrade. The side pieces 13 and 14 are upwardly convergent and have the lower ends thereof formed integrally with the ends of the bottom pieces and joined thereto by substantially right angle bends 15. The side pieces 13 are straight and, due to the angular arrangement of the bottom pieces, have the upper ends thereof disposed adjacent the inner side portion of the rod 10, i. e., the side portion that is nearer the compressible filler strip j. The side pieces 14 of the wire formed U-shaped chairs are straight except for the upper ends thereof and such ends project above the upper ends of the side pieces 13 and function as hereinafter described. Because of the angular arrangement of the bottom pieces 12 with respect to the rod 10 the upper portions of the side pieces 14 are disposed adjacent the outer side portion of the bar aligning rod 10, i. e., the side portion that is farther from the filler strip j.

The brackets 11 are in the form of one-piece plate metal stampings. They are located at the upper portions of the chairs 9 and consist of central parts 16, inner end parts 17 and outer end parts 18. The central parts 16 of the brackets are shaped to define transversely extending semi-circular open top pockets 16^a for the bar aligning rod 10 and consist of bottoms 19 of semi-circular cross section, inner sides 20 and outer sides 21. The inner and outer sides 20 and 21 are joined to, and extend upwards from, the inner and outer side margins of the bottoms 19. As shown in Figure 2, the intermediate parts 16 of the brackets are positioned between the upper ends of the side pieces 13 and 14 of the chairs and are transversely elongated in order that the semi-cylindrical pockets 16^a are comparatively long and hence adequately support the rod 10 when it is in place in the pockets. The inner and outer sides 20 and 21 of the brackets are disposed apart a distance slightly less than the diameter of the rod 10 in order that the rod is snugly gripped or confined when it is inserted into the pockets. The ends of the side pieces 13 of the chairs are positioned against, and are welded to, the adjacent ends of the inner sides 20 of the brackets 11 with the result that the brackets are in fixed or rigid relation with said chair side pieces 13. The inner end parts 17 of the brackets are shaped to define horizontal longitudinally extending semi-circular open top pockets 22 for the adjacent ends of the dowel bars j¹ of the joint J. They are centrally positioned with respect to the central parts 16 of the brackets and consist of bottoms 23 of semi-cylindrical cross section and upstanding sides 24 and 25. The inner ends of the bottoms 23 are joined to, and formed integrally with, the central portions of the upper margins of the inner sides 20 of the bracket central parts 16. The pockets 22 are so positioned with respect to the pockets 16^a that when the adjacent ends of the dowel bars j¹ are in place in the pockets 22 and the bar aligning rod is in

place in the pockets 16^a the portions of the dowel rods that overlie the central parts 16 of the brackets directly engage the subjacent portions of the rod 10 and serve to hold the rod in the pockets 16^a. The sides 24 and 25 of the inner end parts 17 of the brackets extend inwards to a slight extent in order that they grip frictionally the adjacent ends of the dowel bars when said ends are in place in the semi-circular pockets 22. The inner end parts 17 of the brackets are of such length that the pockets 22 securely support the dowel bars and hold them truly normal or at right angles to the bar aligning rod 10. The outer end parts 18 of the brackets consist of substantially flat horizontally disposed bottoms 26 and upstanding sides 27 and together with the upper extremities of the side pieces 14 of the wire formed U-shaped chairs 9 define auxiliary open top pockets 28 for the adjacent ends of the dowel bars *j*¹. The bottoms 26 are joined to, and formed integrally with, the upper marginal portions of the outer sides 21 of the central parts 16 of the brackets and are horizontally aligned with the bottoms 23 of the inner end parts 17 of the brackets. The sides 27 of the outer end parts 18 are longitudinally aligned with the sides 24 of the inner end parts 17 and are joined to, and formed integrally with what may be termed, the inner side margins of the bottoms 26. The outer side margins of said bottoms 26 project outwards beyond the sides 25 of the inner end parts 17 of the brackets and are provided with holes 29 through which extend the upper ends or extremities of the side pieces 14 of the chairs 9. The holes 29 are of greater diameter than the side pieces 14 in order that such pieces are free to flex to and from the side pieces 13. The portions of the upper ends of the chair side pieces 14 that are directly above the bottoms 26 of the outer end parts 18 of the brackets are bent inwards so that the pockets 28 are of the restricted entrance variety and the upper extremities of said upper ends of said side parts 14 are bent outwards, as shown in Figures 4 and 5 of the drawings in order to guide the adjacent ends of the dowel bars *j*¹ into the pockets 28 when the dowel rods are shifted downwards in connection with mounting thereof with respect to the brackets 11. The inwardly bent portions of the upper ends of the side pieces 14 are adapted when the adjacent ends of the dowel bars are in place in the pockets 28 to grip the dowel bars with inward spring pressure and thus serve to hold said adjacent ends of the bars in the pockets 22 and 28. The bends between the lower ends of the side pieces 14 and the adjacent ends of the bottom pieces 12 of the chairs 9 are so designed that they urge the upper ends of said side pieces 14 against the inner portions of the holes 29, as shown in Figure 2. When the dowel bars are shifted downwards into the pockets 22 and 28 the side pieces 14 of the chairs flex outwards due to the fact that the holes 29 are over-sized and hence the inwardly bent portions of the upper ends of the side pieces 14 engage the adjacent portions of the dowel bars with the desired spring action and hold the bars in place in the pockets 22 and 28. As hereinbefore pointed out, the outwardly bent extremities of the upper ends of the chair side pieces 14 serve to guide the dowel bars into the pockets 28 when they are shifted downwards in connection with mounting of the bars relatively to the brackets 11. By reason of the fact that the brackets 11 include the main semi-cylindrical pockets 22 and the auxiliary pockets 28 the dowel bars when in

place in the pockets are rigidly held at true right angles to the bar aligning rod 10.

The combined bar support and spacer 8 on the opposite side of the compressible filler strip *j* is exactly the same in design and construction as the combined bar support and spacer 7. It operates as hereinbefore described to support the adjacent ends of the dowel bars *j*¹ and consists of a horizontal rectilinear series of separately formed and independent upstanding equidistantly spaced chairs 30 and a horizontally extending rod 31. The chairs 30 are aligned with the chairs 9 and are the same in construction and design as the latter. They are U-shaped and have at the upper portions thereof brackets 32 which are like the brackets 11 and have transversely extending semi-cylindrical pockets 33 for the rod 31, longitudinally extending semi-cylindrical pockets 34 for the adjacent ends of the dowel bars *j*¹ and auxiliary pockets 35 in longitudinal alignment with the pockets 34. The rod 31 is horizontally aligned with the rod 10 and serves horizontally to align the dowel bars.

In assembling the joint and unit of Figure 1 the chairs 9 of the combined support and spacer 7 are arranged in a rectilinear series on the subgrade S². Thereafter the rod 10 is shifted downwards into the pockets 16^a in the central parts 16 of the brackets 11. After positioning of the rod in the pockets 16^a the rod is positioned so that it extends truly crosswise of the subgrade. After assembly of the combined bar support and spacer 7, the combined bar support and spacer 8 is assembled by arranging the chairs 30 in a rectilinear series over the subgrade S² and shifting the bar aligning rod 31 downwards into the pockets 32 in the central parts of the brackets 32 at the upper portions of the chairs 30. After assembly of the combined bar support and spacer 8 the latter is arranged so that the rod 31 extends truly crosswise of the subgrade and is spaced from the rod 10 a distance less than the length of the dowel bars. After the combined bar support and spacers 7 and 8 are properly arranged with respect to the subgrade the dowel bars *j*¹ are inserted through the holes in the central portion of the compressible filler strip *j* and the filler strip and bars are manipulated so as to bring the lower margin of the strip into abutment with the subgrade and the ends of the dowel bars into seated relation with the pockets in the inner and outer end parts of the brackets 11 and 32. When the dowel bars are seated in such pockets they are maintained by the combined supports and spacers 7 and 8 in a truly horizontal position and also at true right angles to the compressible filler strip *j*. After assembly of the joint and unit concrete is poured at the sides of the strip *j* to form the slabs S⁶⁰ and S¹. After setting of the concrete the dowel bars form load transfer members as hereinbefore pointed out. By reason of the fact that each of the brackets is provided with two pockets for the dowel bar with which it is associated there is no likelihood of either of the combined bar supports and spacers moving lengthwise with respect to the other bar support and spacer in connection with either assembly of the unit or pouring of the concrete at the sides of the compressible filler strip and the bars are maintained in true parallel relation.

The herein described combined bar support and spacer is essentially simple in design and hence may be manufactured at a low and reasonable cost. It effectively and efficiently fulfills

its intended purpose and is characterized by the fact that the double pocket arrangement at the upper portions of the chairs serves positively to hold the bars so that they are truly normal or at right angles to the bar aligning rod at the upper portions of the chairs.

Whereas the combined bar support and spacer has been described as adapted for use in conjunction with a complementary combined support and spacer to form a unit for use in connection with a concrete roadway joint it is to be understood that the invention contemplates a single combined bar support and spacer having other capabilities of use. It is also to be understood that the invention comprehends a single bar supporting chair like that shown in Figure 2, and is not to be restricted to the details set forth since these may be modified within the scope of the appended claims without departing from the spirit and scope of the invention.

Having thus described the invention, what I claim as new and desire to secure by Letters Patent is:

1. A combined support and spacer for laterally spaced horizontally disposed parallel bars, comprising a bar aligning rod adapted to be positioned directly under and at right angles to the bars, and a rectilinear series of separately formed and independent upstanding laterally spaced wire formed U-shaped chairs positioned along the rod, corresponding in number to, and adapted to be associated respectively with, the bars, and each including a pair of upwardly convergent side pieces, and embodying a one-piece stamped metal bracket connected fixedly to the upper end of one of the side pieces and having a part thereof shaped to form an elongated semi-cylindrical open top pocket for receiving and supporting the rod, and another part thereof consisting of a bottom adjacent and to one side of the upper portion of the bottom and an upstanding side, arranged so that it forms with the upper end of the other side piece an open top restricted entrance pocket for receiving and supporting the associated bar.

2. A combined support and spacer for laterally spaced horizontally disposed parallel bars, comprising a bar aligning rod adapted to be positioned directly under and at right angles to the bars, and a rectilinear series of separately formed and independent upstanding laterally spaced wire formed U-shaped chairs positioned along the rod, corresponding in number to, and adapted to be associated respectively with, the bars, and each including a pair of upwardly convergent side pieces, and embodying a one-piece stamped metal bracket connected fixedly to the upper end of one of the side pieces and having a part thereof shaped to form an elongated semi-cylindrical open top pocket for receiving and supporting the rod, and another part thereof consisting of a substantially flat bottom adjacent and to one side of the pocket together with an upstanding side, provided in its bottom with an over-sized hole in opposed relation with said side and through which the upper end of the other side piece extends, and forming with said upper end of said side piece an open top restricted entrance auxiliary pocket in alignment with the second mentioned pocket and adapted also to receive and support said associated bar.

3. A combined support and spacer for laterally spaced horizontally disposed parallel bars, comprising a bar aligning rod adapted to be positioned directly under and at right angles to the bars, and a rectilinear series of separately formed and independent upstanding laterally spaced wire formed U-shaped chairs positioned along

the rod, corresponding in number to, and adapted to be associated respectively with, the bars, and each including a pair of upwardly convergent side pieces and embodying a horizontally elongated one-piece stamped metal bracket having the central portion thereof fixedly connected to the upper end of one of the side pieces and shaped to form an elongated transversely disposed semi-cylindrical open top pocket for receiving and supporting the rod, one of its end parts shaped to form a longitudinally extending semi-cylindrical open top pocket disposed directly above and at right angles to the first mentioned pocket and adapted to receive and support the associated bar, and its other end part consisting of a bottom adjacent the upper portion of said first mentioned pocket and an upstanding side and forming with the upper end of the other side piece an open top restricted entrance auxiliary pocket positioned in alignment with the second mentioned pocket and also adapted to receive said associated bar.

4. A combined support and spacer for laterally spaced horizontally disposed parallel bars, comprising a bar aligning rod adapted to be positioned directly under and at right angles to the bars, and a rectilinear series of separately formed and independent upstanding laterally spaced wire formed U-shaped chairs positioned along the rod, corresponding in number to, and adapted to be associated respectively with, the bars, and each including a pair of upwardly convergent side pieces and embodying a horizontally elongated one-piece stamped metal bracket having the central portion thereof fixedly connected to the upper end of one of the side pieces and shaped to form an elongated transversely disposed semi-cylindrical open top pocket for receiving and supporting the rod, one of its end parts shaped to form a longitudinally extending semi-cylindrical open top pocket disposed directly above and at right angles to the first mentioned pocket and adapted to receive and support the associated bar, and its other end part consisting of a substantially flat bottom adjacent and outwards of the upper portion of said first mentioned pocket and an upstanding side, provided in its bottom with an over-sized hole in opposed relation with said side and through which the upper end of the other side piece extends, and defining with said upper end of said side piece an open top restricted entrance auxiliary pocket in alignment with the second mentioned pocket and adapted also to receive and support said associated bar.

5. As a new article of manufacture, a chair adapted to support a horizontally disposed reinforcing bar and comprising an upstanding wire formed U-shaped member having the side pieces thereof upwardly convergent and adapted to flex to and from one another, and a stamped metal bracket connected fixedly to the upper end of one of the side pieces of the member and including a part embodying a substantially flat horizontal bottom and an upstanding side, and forming with the upper end of the other side pieces of said member an open top restricted entrance pocket for receiving the bar.

6. As a new article of manufacture, a chair adapted to support a horizontally disposed reinforcing bar and comprising an upstanding wire formed U-shaped member having the side pieces thereof upwardly convergent and adapted to flex to and from one another, and a stamped metal bracket connected fixedly to the upper end of

one of the side pieces of the member and including a part embodying a substantially flat horizontal bottom and an upstanding side, provided in the bottom thereof with a hole in opposed relation with said side and through which the upper end of the other side piece extends, and forming with said upper end of the side piece an open top restricted entrance pocket for receiving and supporting the bar.

7. As a new article of manufacture, a chair adapted to support a horizontally disposed reinforcing bar and comprising an upstanding wire formed U-shaped member having the sides thereof upwardly convergent and adapted to flex to and from one another, and a horizontal elongated stamped metal bracket connected fixedly to the upper end of one of the side pieces and having one of the end parts thereof shaped to form a longitudinal semi-cylindrical open top pocket for the bar and its other end part embodying a substantially flat horizontal bottom and an upstanding side, and forming with the upper end of the other side piece an open top restricted entrance auxiliary pocket disposed in alignment with the first mentioned pocket and also adapted to receive the bar.

8. As a new article of manufacture, a chair adapted to support a horizontally disposed reinforcing bar and comprising an upstanding wire formed U-shaped member having the sides thereof upwardly convergent and adapted to flex to and from one another, and a horizontal elongated stamped metal bracket connected fixedly to the upper end of one of the side pieces and having one of the end parts thereof shaped to form a longitudinal semi-cylindrical open top pocket for the bar and its other end part embodying a substantially flat horizontal bottom and an upstanding side, provided in its bottom with an over-sized hole in opposed relation with said side and through which the upper end of the other side piece extends, and forming with said upper end of the other side piece an auxiliary open top restricted entrance pocket disposed in alignment with the first mentioned pocket and also adapted to receive and support the bar.

9. As a new article of manufacture, a chair adapted to support a pair of horizontally disposed crossed bars and comprising an upstanding wire formed U-shaped member having the side pieces thereof upwardly convergent and adapted to flex to and from one another, and a stamped metal bracket connected fixedly to the upper end of one of the side pieces and having a part thereof shaped to form an elongated horizontally disposed semi-cylindrical open top pocket for receiving and supporting the lower bar, and another part thereof embodying a substantially flat horizontal bottom adjacent and projecting outwards from the upper portion of said pocket and in addition an upstanding side, and forming with the upper end of the other side piece an open top restricted entrance pocket for receiving and supporting the other bar.

10. As a new article of manufacture, a chair adapted to support a pair of horizontally disposed crossed bars and comprising an upstanding wire formed U-shaped member having the side pieces thereof upwardly convergent and adapted to flex to and from one another, and a stamped metal bracket connected fixedly to the

upper end of one of the side pieces and having a part thereof shaped to form an elongated horizontally disposed semi-cylindrical open top pocket for receiving and supporting the lower bar, and another part thereof embodying a substantially flat horizontal bottom adjacent and projecting outwards from the upper portion of said pocket and in addition an upstanding side, provided in said bottom thereof with an oversized hole in opposed relation with said side and through which the upper end of the other side piece extends, and forming with said upper end of the other side piece an open top restricted entrance pocket for receiving the upper bar.

15. 11. As a new article of manufacture, a chair adapted to support a pair of horizontal bars arranged one directly above the other and at right angles to one another, and comprising an upstanding wire formed U-shaped member having the side pieces thereof upwardly convergent and adapted to flex to and from one another, and a horizontally elongated one-piece stamped metal bracket connected fixedly to the upper end of one of the side pieces and having the central portion thereof shaped to form an elongated transversely extending semi-cylindrical open top pocket for receiving and supporting the lower bar, one of its end parts shaped to form a horizontally extending semi-cylindrical open top pocket disposed directly above and at right angles to the first mentioned pocket and adapted to receive and support the upper bar, and its other end part embodying a substantially flat horizontal bottom adjacent the upper portion of said first mentioned pocket and in addition an upstanding side, and forming with the upper end of the other side piece an open top restricted entrance pocket disposed in alignment with the second mentioned pocket and adapted also to receive and support the upper bar.

12. As a new article of manufacture, a chair adapted to support a pair of horizontal bars arranged one directly above the other and at right angles to one another, and comprising an upstanding wire formed U-shaped member having the side pieces thereof upwardly convergent and adapted to flex to and from one another, and a horizontally elongated one-piece stamped metal bracket connected fixedly to the upper end of one of the side pieces and having the central portion thereof shaped to form an elongated transversely extending semi-cylindrical open top pocket for receiving and supporting the lower bar, one of its end parts shaped to form a horizontally extending semi-cylindrical open top pocket disposed directly above and at right angles to the first mentioned pocket and adapted to receive and support the upper bar, and its other end part embodying a substantially flat horizontal bottom adjacent the upper portion of said first mentioned pocket and in addition an upstanding side, provided in the bottom thereof with an over-sized hole in opposed relation with said side and through which the upper end of the other side piece extends, and forming with said upper end of the other side piece an open top restricted entrance pocket disposed in alignment with the second mentioned pocket and also adapted to receive and support the upper bar.

BROR HILLBERG.
